UNITED STATES PATENT OFFICE.

LUTHER S. AYER, OF WINCHESTER, MASSACHUSETTS, ASSIGNOR, BY MESNE ASSIGNMENTS, TO ALMA MANUFACTURING COMPANY OF BALTIMORE CITY, OF BALTIMORE, MARYLAND, A CORPORATION OF MARYLAND.

BUCKLE.

1,080,672.

Specification of Letters Patent.

Patented Dec. 9, 1913.

Application filed February 26, 1908. Serial No. 417,961.

To all whom it may concern:

Be it known that I, LUTHER S. AYER, a citizen of the United States, and resident of Winchester, in the county of Middlesex and 5 State of Massachusetts, have invented an Improvement in Buckles, of which the following description, in connection with the accompanying drawings, is a specification, like letters on the drawings representing like 10 parts.

This invention pertains to buckles; and consists in certain features of construction which contribute to make a buckle more convenient in use, more effective in the performance of its gripping or biting office and more economical in manufacture.

The character of the invention may be best understood by reference to the accompanying drawings, which show for purposes 20 of illustration one practicable embodiment of the invention.

In the drawings,—Figure 1 is a plan view of a buckle embodying features of this invention; Fig. 2 is a central longitudinal section on the line 2—2 of Fig. 1; and, Fig. 3 is an enlarged detail of the section shown in Fig. 2.

The specific illustrative buckle consists of a body portion 5, preferably stamped out to 30 supply a transverse barrel or socket 6, which may be provided conveniently by forcing down some of the originally flat material of the body portion and bending the same into the form of a hollow cylinder extending 35 across the buckle. The illustrative barrel 6 serves as the means of attaching the buckle permanently to the strap *n*, as by folding the latter over the barrel and sewing it across in the well-known manner. The 40 barrel is preferably bodily offset from the top plane of the buckle, in order that the overlying thickness of the attached strap may be nearly flush with the top surface 45 of the body portion 5, giving a flat appearance to the buckle. The body portion 5 supplies also a lever end 7 and a jaw 8. To 50 co-operate with the jaw 8 is a strap-gripping bar 9, itself preferably substantially inflexible, so that throughout its length it shall be 55 capable of a firm gripping co-operation with the jaw 8. The bar 9 forms part of a U-shaped tongue which may be merely a piece 60 of strong wire appropriately bent and hav-

ing its ends turned inwardly to form pivot members 10, 10, preferably of extensive 55 length, projecting into the interior of the barrel 6, which supplies a fulcrum for the tongue and the bar 9.

The specific supporting tongue having the bar 9, is bent to form upturned necks 11, 11 60 which permit the bar 9 to stand substantially opposite or, if desired, somewhat above the jaw 8, while the remainder of the tongue lies beneath the body portion 5. In order to define the normal position of the bar 9 65 with relation to the jaw 8, the body portion 5 may be formed to provide stop surfaces 12, 12 against which parts 13 of the tongue may abut or rest.

The bar 9 is itself preferred to be substantially inflexible and the tongue is permitted to yield somewhat lengthwise of the buckle by having the pivot members 10, 10 70 inclined slightly rearwardly (*i. e.* away from the jaw 8), or otherwise arranged so 75 that a pull on the bar 9 may slide the pivot members 10, 10 axially and withdraw them slightly from the barrel 6 to permit bodily movement of the tongue toward and from the jaw 8. The resiliency of the wire tongue 80 serves to keep the pivot members 10, 10 normally properly positioned in the barrel 6.

When desired, the jaw 8 is concaved, as shown, or otherwise recessed to give separated bearing surfaces to engage a strap near 85 its lateral edges. The concavity in the jaw 8 may serve to accommodate an enlargement or augmented thickness along the strap such, for example as occurs at the seam.

To promote security of grip on the strap, 90 one or the other, or both, of the jaw 8 and the bar 9 may have angular portions such, for example, as are illustrated in Fig. 3. As there shown, the jaw 8 has an angular upwardly projecting lip 18 to coöperate with 95 a lip 20 on the bar 9.

Preferably one or the other of the lips may be slightly rounded at its edge to permit the other to slide readily over it and bite thereon. With this arrangement the 100 gripping of a strap between the lips 18 and 20 causes the strap, when pulled, to pucker or wrinkle in the rear of the jaws and to bear against the converging faces of the lips 18 and 20, with a tendency to force them 105 into closer contact and increase the grip.

The stop surfaces 12, 12 may contribute to the effective coöperation of the lips 18 and 20, as by determining their proper relations.

The above described illustrative construction supplies an effective system of lever actions contributing to the security of the buckle's grip and the effectiveness of its holding power, as will be appreciated by those familiar with the art. The permanently attached strap *n* encircles the barrel 6 and the free strap 15 has its end gripped between the bar 9 and the jaw 8. In use, considerable pulls are exerted on both said straps in opposite directions, as indicated by the arrows, and those pulls co-act to secure firm engagement of the free strap by the strap-gripping surfaces. For example, the pull on strap *n* exerts a force on the lever end 7 thereof in the direction of the arrow 16, thus constituting the body portion 5 in effect a lever of the first-class with its fulcrum in the axis of the barrel 6 and its acting end at the jaw 8. The lever end of the frame is curved in cross-section so that the strap attached to the fulcral socket will exert a clamping pressure. This lever action of the body portion tends to move the jaw 8 contra-clockwise in Fig. 2, *i. e.* toward its initial strap-engaging relation with the bar 9 when the strap 15 is first introduced and tightened. When, however, the jaw 8 and bar 9 assume the positions shown in Fig. 2 the tongue or bail abuts against the stop surfaces 12, 12, which determine the final strap-gripping relations of the jaws and oppose the downward tendency of the jaw 8. In other words, the normal pull upon the strap *n* tends to rock the lever end 7 and body portion contra-clockwise, while the pull on the strap 15 tends to force the bar 9 and tongue clockwise; when the tongue strikes the stop surfaces 12, 12, on the body portion these opposite tendencies balance and the buckle is held perfectly flat with its strap-engaging parts in their proper relation, determined by said stop surfaces. It is an advantage of the specific construction disclosed that, in creating the said rotary tendency, the respective straps act upon opposite extremities of the buckle, *i. e.* upon the extreme lever end 7 and upon the opposite extremity, the bar 8; and all the rotary tendencies are about the same axis of the barrel 6. With this arrangement there is every tendency to hold the entire buckle flat against the strap in a manner which would be impossible if the strap *n* were attached to the buckle at some point between the barrel 6 and the jaw 8, or, in other words, at some point between the axis of movement of the tongue or barrel and the strap-engaging jaw of the body portion. With such a construction as that just suggested, the tendency would be to force the end 7 upwardly from the strap *n*, causing a gap between them.

While the invention is not essentially limited to the specific embodiment shown in the drawings, the latter is a preferred form and presents all the advantages supplied by the features of the invention.

No attempt has been made hereinbefore to define the scope of the invention, that office being delegated exclusively to the subjoined claims.

Claims—

1. A buckle comprising, in combination, a body-portion having a jaw recessed to provide separated strap-engaging surfaces; a U-shaped tongue providing a substantially straight inelastic strap-engaging bar extending across said separated surfaces to coöperate with said jaw; inturned pivot-members of extensive length formed by the extremities of the tongue, said members being inclined rearwardly away from said jaw, substantially in the plane of the buckle; and a transverse barrel formed on the body portion to receive the pivot-members and supply therefor extended journal bearings, whereby the pivot-members may be partly withdrawn from said bearings under pull on the tongue, while preserving effective pivotal support therefor. 90

2. A buckle, having a body portion comprising a lever end, a jaw at the opposite end formed on its outer edge with a transverse lip projecting upwardly at an angle thereto, and an intermediate transverse socket, combined with a U-shaped tongue pivotally mounted in the socket and underlying the body portion and having upturned necks and a transverse bar supported by said necks with its bottom substantially in advance of and opposite the upper edge of the lip, the tongue being capable of yielding longitudinally with relation to the frame and adapted to grip a strap between its bar and the lip of the jaw. 95

3. A buckle, having a body portion 5 comprising lever end 7, a jaw end 8 provided with an upturned lip 18 extending transversely of the jaw, and an intermediate tongue-receiving means, combined with a U-shaped tongue pivoted in said means below the body portion and having its sides parallel with the sides of the body portion and extended beyond the upturned lip and terminating in a transverse bar in advance of the jaw end, said tongue capable of yielding longitudinally under stress of a tightening strap to be 120 engaged and at such time to be drawn into gripping relation with the jaw end. 115

4. A buckle comprising, in combination, a body-portion having a jaw recessed to provide separated upwardly projecting strap-engaging surfaces, a U-shaped tongue providing a substantially straight inelastic strap-engaging bar extending across said separated surfaces outside of the body portion to coöperate with said jaw, inturned 125

pivot-members of extensive length formed by the extremities of the tongue, and a transverse barrel formed on the body portion to receive the pivot members and supply there-
5 for extended journal bearings, the tongue having a yielding motion in the direction of its length as it is put under tension by the strap and thereby drawn into gripping relation to the jaw.

In testimony whereof, I have signed my 10 name to this specification, in the presence of two subscribing witnesses.
